(57) **CLAIM**

I claim the ornamental design for a cable sleeve, as shown and described.

DESCRIPTION

FIG. 1 is a perspective view of a cable sleeve, showing my new design;

FIG. 2 is a second perspective view thereof;

FIG. 3 is a front elevational view thereof, the rear elevational view being a mirror image thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken line showing in FIG. 1 represents unclaimed subject matter and forms no part of the claimed design. The cable sleeve has been shown broken to indicate indeterminate length.
